UNITED STATES PATENT OFFICE.

ELBERT C. TAYLOR, OF STOCKTON, MISSOURI.

CHURN.

SPECIFICATION forming part of Letters Patent No. 333,358, dated December 29, 1885.

Application filed May 15, 1885. Serial No. 165,632. (No model.)

To all whom it may concern:

Be it known that I, ELBERT C. TAYLOR, of Stockton, Cedar county, Missouri, have invented certain new and useful Improvements 5 in Churns, of which the following is a specification.

My invention relates particularly to the class of working-body churns, and most of my improvements are designed to increase the efficiency of such churns; but certain parts of my 10 invention are not so limited in their application, but may be used in churns of other classes.

In the accompanying drawings, Figure 1 is an elevation of my improved churn; Fig. 2, a 15 vertical section of the same; Fig. 3, a vertical section of the churn-body, showing my improved dasher; and Fig. 4, a section of the same on the line 4 4 of Fig. 3.

I will describe my improvements as I prefer 20 to organize them; but obviously many changes in the details of construction may be made without departing from my invention.

The supporting-frame A is made of metal. In the drawings it is shown as constructed of 25 a single piece of bar-iron, bent at a to form a horizontal support and brace, a' . From a the bar is extended up on both sides in graceful curves a^2 , and looped at a^3 to form bearings for the journals of the churn-body. It 30 is then extended down on both sides in curves corresponding to a^4 , and then bent at a^5 , to form feet a^6 .

The frame for carrying the churn-body is divided into two parts, B' and B². The part 35 B' consists of a rod, that is bent at b' to form a horizontal cross-piece, b^2 , and two parallel hangers, b^3 . The hangers are bent at b^4 to form journals b^5 and b^6 , that enter the bearings a^3 . The journal b^5 is prolonged into a crank, b^7 , 40 on which is pivoted a handle, b^8 . The part B' is also made of a rod bent to form two parallel arms, b^9 , and a cross-piece, b^{10} . The arms b^9 are hinged to the journals b^5 b^6 of the part B'.

The churn-body C consists of a cylinder, c , 45 closed at the bottom, and provided with a removable top, c' . The top c' is formed with an annular groove or seat, c^2 , for the rim of the cylinder. The seat c^2 is preferably wedge-shaped, so as to make a tighter fit with the cylinder. The top c' is provided with a reinforcing cross-piece, c^3 , that forms a bearing 50 for the set-screw D. The set-screw D works

in a nut, d , in the cross-piece d' , that is connected to the frame B² by straps d^2 . The frame B² is preferably bent at b^{11} , to accommodate 55 the screw. The bottom of the cylinder rests on a circular base-board, E, that is attached to the frame B' by straps e . The belt F, which is preferably elliptical, as shown, surrounds the middle of the cylinder, and is secured to 60 the frame B' B², so as to move with it in its revolutions. It serves to prevent the cylinder from tipping too far when not held in place by the set-screw. It will be observed that the set-screw not only holds the top on the cylinder, but also holds the churn-body firmly in 65 its frame.

Two forms of dasher are shown in the drawings. In Fig. 2 the dasher is shown as consisting of a perforated diaphragm, G, attached 70 to a staff, g, that is secured to the top of the cylinder. Figs. 3 and 4 illustrate my improved form of dasher. It consists of a diaphragm or disk, H, about equal in diameter to the interior of the cylinder, and when in working 75 position located about midway between its ends. The edges of the disk are formed with recesses or notches h , and the body of the disk may be perforated, as shown at h' . The top of the disk is provided with a knob, h^2 , for 80 convenience of handling. Brackets I, corresponding in number to the notches h , are secured to the interior of the cylinder about half-way down, and serve to hold the disk H 85 in place. The brackets are preferably each formed of a base, i, and two parallel lugs, i', that embrace the edge of the disk when in position. The disk is set in place by lowering it in the cylinder until the notches coincide with the intervals between the lugs i', and then 90 giving it a slight turn until its edge rests on the bottom lugs. The dasher in both instances divides the cylinder into two compartments. When the crank is turned, the cylinder is 95 revolved and its contents are thrown from one compartment to the other. As the milk or cream leaves one compartment it is replaced by air from the other compartment. This operation is continued until the churning is completed.

The cylinder may be conveniently put in position and removed by swinging the frame B² on its hinges.

I am aware that churn-bodies have been

mounted in frames or hangers that are mounted in a supporting-frame.

I am also aware that the top of the churn-body has been held on by means of tie-rods.

5 It has also been proposed to construct a supporting-frame by bending iron rods or wires to form standards and journal-bearings for a rotary or swinging cylinder.

I claim as my invention—

10 1. The combination, substantially as set forth, of the supporting-frame, the churn-body, its top, and the frame journaled in the supporting-frame that carries the churn-body and is made in two parts, hinged together, 15 whereby the upper part of the frame may be swung away so that the top of the churn-body may be removed.

20 2. The combination, substantially as set forth, of the supporting-frame, the churn-body, the hangers that support the churn-body and are bent to form journals on which the churn-body revolves, and the frame that holds the churn-body in position between the hangers.

25 3. The combination, substantially as set forth, of the supporting-frame, the hangers journaled in the supporting frame, the churn-body supported at one end by the hangers,

and the screw-carrying frame hinged to the hangers that holds the churn-body in position. 30

4. The combination, substantially as set forth, of the churn-body, the supporting-frame, the hangers journaled in the supporting-frame, the screw-carrying frame hinged to the hangers, the cross-piece carrying the nut, 35 and the screw.

5. The combination, substantially as set forth, of the cylinder, the brackets formed with two lugs secured thereto, the perforated dasher having notches in its edges that normally rest between the lugs, and the handle for the dasher, substantially as described. 40

6. A churn-frame formed of a single bar of metal bent at a to form a horizontal support and brace, a' , extended up on both sides 45 and looped at a^3 , to form bearings for the journals of the churn-body, and then extended down and bent at a^4 to form feet a^5 , substantially as set forth.

In testimony whereof I have hereunto subscribed my name.

ELBERT C. TAYLOR.
